(57) CLAIM

The ornamental design for display screen or portion thereof with graphical user interface, as shown and described.

DESCRIPTION

FIG. 1 is a front view of a display screen or portion thereof with graphical user interface showing our new design. The evenly spaced broken lines illustrate a display screen or portion thereof and form no part of the claimed design. The dotted broken line showing of “names” illustrates portions of the graphical user interface that form no part of the claimed design.

1 Claim, 1 Drawing Sheet
